FLUID COOLED DOUBLE ACTING PISTONS FOR HIGH TEMPERATURE ENGINES

Harry M. Arnold, 222 S. 5th St., Douglas, Wyo.

Filed May 5, 1960, Ser. No. 27,020

4 Claims. (Cl. 121—1)

This invention relates to double acting piston engines and piston valves utilizing highly heated gases and, or, highly superheated steam for reciprocating a piston in the engine cylinder.

The main object of my invention is to provide improved means for circulating a cooling agent or cooling, sealing and lubricating agent through the piston and, or, piston valves of an engine of the character stated. Efforts have been made to circulate such agents through engine pistons but the mechanisms heretofore devised for that purpose have employed flexible connections, a change in volume or intermittent flow, which have proven to be inefficient and unsatisfactory in use.

Other objects and advantages of the invention will become apparent from the drawings and following specification in which like numbers designate like or similar parts throughout the several views and in which:

FIG. 1 is a longitudinal sectional view of one type of a long double acting piston and a cylinder barrel embodying my invention.

FIG. 2 is a cross-sectional view of FIG. 1 on the section line 2—2 and shows the passageways for the circulating agent.

FIG. 3 is a longitudinal sectional view of another type of a long piston and a cylinder barrel embodying my invention.

FIG. 4 is a cross-sectional view at 4—4 of FIG. 3 and shows the passageways for the circulating agent.

FIG. 5 is a longitudinal sectional view of one type of piston poppet valve provided with my means of cooling.

FIG. 6 is a longitudinal sectional view of another type of piston poppet valve provided with my means of cooling.

FIG. 7 is a longitudinal sectional view of a piston and cylinder barrel having additional inlets and outlets for the circulating agent.

FIG. 8 is a cross-sectional view of FIG. 7 on the section line 8—8 showing the passageways into and out of the jackets in the piston heads.

FIG. 9 is a modification view of FIG. 1, showing jackets in the piston heads and a division in the entering passageway.

FIG. 10 is an exact cross-section of FIG. 9 on the section line 10—10 and shows the jackets and bridge dividing the entering passageway.

FIG. 11 is a longitudinal sectional view of a long piston provided with webbed heads for conducting heat to the jacketing system.

FIG. 12 is an exact cross-section of FIG. 11 on the section line 12—12 and shows details of the webs.

Referring to FIG. 1, which gives the general idea of my circulating means, the numeral 10 indicates cylinder heads closing the ends of the cylinder 11 while the long piston 12, with plain piston heads, is free to reciprocate in the cylinder 11. The piston 12 is provided with the usual piston rod 13 and piston rings or other means 14 to secure a seal at the ends of the piston 12. Channels are provided around the ends of the piston 12 for holding the circulating agent as shown at the section line 2—2 and K—K. The center of the cylinder 11 is also provided with a channel completely around its inside as shown at the section line 2—2 in dotted lines and it is clearly shown in FIG. 2 in solid lines. An inlet on one side and an outlet on the opposite side for the circulating agent to enter and leave can be seen.

2

It is to be noted in this design, the circulating agent enters one of the passageways at 2—2 and circulates around the piston 12 and leaves from the opposite opening at 2—2 in the cylinder 11. The chambers around the ends of the piston 12 at 2—2 and K—K trap a portion of the circulating agent and carry it along the barrel of the cylinder 11 each way from the central passageway in the cylinder 11 at 2—2. The central portion of the piston 12 travels back and forth through a steady stream of fluid while the end portions of the cylinder barrel 11 are alternately exposed to the fluid trapped in the channels around the end portions of the piston 12. Both the piston 12 and cylinder barrel 11 are exposed directly to the circulating agent. A pocket 20 may be provided in the side of the piston 12 so a rod or bar can be inserted at one of the openings at 2—2 to hold the piston from rotating out of proper position while assembling the engine mechanism.

In FIG. 2, taken on the section line 2—2 of FIG. 1, 20 is shown one of the channels in the piston 12 and the larger channel around this in the cylinder barrel 11. The plain piston heads shown at the ends of the piston 12 in FIGS. 1 and 2 will conduct heat to the jacketing system around the ends of the piston 12. When the channels around the piston 12 are not in communication with the inlet and outlet at 2—2 in the cylinder 11 the circulating agent can continue to circulate around the outside of the piston 12 and through the jackets in the heads at 2—2 in the cylinder 11 until again acted upon at 2—2 in the cylinder barrel 11.

FIG. 3 shows the general idea of my circulating means applied to a different design of piston 12 and cylinder barrel 11. The fluid enters one of the openings at 4—4 and is all forced to pass around and through the spool type piston 12, as indicated by arrows. The passageways in the cylinder barrel 11 at 4—4 do not continue completely around the piston 12 as is the case in FIGS. 1 and 2. In order to restrict the flow of fluid directly around the outside of the spool type piston 12 a partition 18, shown in dotted lines, can be provided along each side of the piston 12 allowing a much smaller clearance between the cylinder barrel 11 and piston 12 at this point. Since only a part of the fluid can pass these partitions 18 the remainder of the fluid must pass through the jackets 19 in the heads of the piston 12. After the fluid passes around and through the jackets 19 in the heads of the piston 12 it leaves the cylinder 11 at the opposite opening at 4—4, as shown by arrows. It is to be noted the circulating agent contacts a much greater area of both the piston 12 and cylinder barrel 11 than is the case in FIGS. 1 and 2 and that the long passageway around the outside of the piston 12 is always in communication with the inlet and outlet passageways at 55 4—4.

The FIG. 4 is a cross-sectional view of one end of the piston 12 and cylinder 11 on the section line 4—4 of FIG. 3 and shows the inlet and the outlets in the ends of the piston 12. A very large area in the piston 60 12 is cooled by the circulating agent; see arrows. The ends of the partitions 18, which are optional, can be seen.

FIG. 5 shows the idea of FIG. 3 applied to the piston portion of a piston poppet valve 16. Heat is conducted from the valve end to the spool type of chamber at 16 65 around the piston portion of the valve. No partitions 18 are used in this design and all the fluid passes around the outer surface of the piston 16.

FIG. 6 shows a more complicated construction of a double open end piston poppet valve 16 embodying the 70 idea of FIG. 3. In this case partitions 18, shown in dotted lines, may be used to restrict the flow of fluid around the outside of the piston portion of the valve 16.

Most of the fluid must pass into and around the inside of the valve end of the piston 16 before it can leave through the opposite opening, as shown by arrows. In this construction the entire inside of the valve is cooled by the circulating agent.

In both FIGS. 5 and 6 an opening 21 is provided into the spring chambers for a gas under pressure to enter to assist the springs 17 in holding the valves 16 closed when released by the valve opening means. In these views the numeral 13 indicates the usual valve rod.

FIG. 7 shows the assembly of FIG. 3 equipped with several passageways, channels, inlets and outlets. The circulating agent enters alternate passageways and leaves the passageways inbetween. FIG. 8 taken on the section line 8—8 of FIG. 7 shows fluid entering at 8—8 and leaving at outlets 23 and 24, as shown by arrows in both views. The outlet 23 is shown in dotted lines in FIG. 7. The outlet 24 is in the half of FIG. 7 which was removed.

FIG. 8 shows passageways 25 into and out of the jacketing system 19 in the heads of the piston 12 of FIG. 7. Partitions 18 along the piston 12 restrict the flow directly around the piston 12. When the construction of FIGS. 7 and 8 is used in large size engines the piston 12 can be balanced by allowing the fluid to enter at several inlets and leave at properly located outlets. If all the incoming fluid enters against one side of the piston 12, it will be crowded to the opposite side of the cylinder 11 and will cause excessive wear.

In FIG. 9 the heads of the piston 12 are provided with jackets for the circulating agent. The end of the piston rod 13 is surrounded by a jacket. The bridge or partition 15 in the entering passageway divides the circulating agent and restricts its flow sufficiently to send it at high velocity each way around the trunk of the piston 12 in the channel provided at 10—10 around the inside of the cylinder 11. The side thrust on the piston 12 is relieved. A partial vacuum or low pressure area is formed under the bridge 15 which induces a flow of the circulating agent through the jackets in the heads of the piston 12, when the jackets around the piston at 10—10 and K—K are in communication with the inlet, outlet and channel around the inside of the cylinder 11 at 10—10.

FIG. 10, which is taken on the section line 10—10 of FIG. 9, shows the details of the flow of the circulating agent; see arrows. The fluid going at high velocity each way around the trunk of the piston 12 meets at the outlet at the bottom. Some of the fluid leaves the outlet at the bottom while a part of it is syphoned up through the jackets in the piston heads of the piston 12. When the chambers around the piston 12 at 10—10 and K—K are not in communication with the fluid going around the inside of the cylinder 11 the fluid in the jackets of the piston 12 can continue to circulate through and around the piston 12.

FIG. 11 is a longitudinal sectional view through two of the webs 22 in each end of the piston 12. It can be seen how the webs 22 conduct the heat to the spool type passageway around the trunk of the piston 12 as indicated by dotted lines extending the full length of the spool type passageway. While the webs 22 are applied to a spool type of piston 12 as used in FIG. 3, the webbed construction 22 can also be used in the heads of the pistons of FIGS. 1 and 7 and in the piston poppet valves FIGS 5 and 6.

FIG. 12, taken on the section line 12—12 of FIG. 11 shows the webs 22 in cross-section at the piston rod end. It can be seen how the webs 22 conduct heat away from the hub surrounding the piston rod 13. The partitions 18, which are optional, can be seen in cross-section. They may extend from one end of the spool type of passageway to the other end if desired.

From the description of the means for circulating a cooling agent, or cooling, sealing and lubricating agent through pistons shown herein, it will be noted the mecha-

nism is entirely free of flexible connection and changes in volume as the piston 12 reciprocates and a large continuous opening is provided for all positions of the piston 12 and piston-poppet valves 16. The piston moves all together as one piece while the cylinder is a solid unit with no flexible joints.

By circulating the fluid through the pistons under sufficient pressure the hot gases expanding behind the heads of the piston will not be able to blow past the rings or other sealing means at the ends of the piston. Graphite, or other lubricants of sufficient body can be sent through in the circulating agent to lubricate and seal the rings against leakage into the ends of the cylinders 11.

In the appended claims, the expression "circulating agent" is employed to designate a cooling medium or a cooling, sealing and lubricating agent, whichever may be employed. Water, oil, wet air, saturated steam and other wet gases, liquids or vapors may be used in this circulating system. A surface made wet with water or moisture conducts heat away 40 times faster than a dry surface exposed to a dry gas. When one pound of water or moisture evaporates at atmospheric pressure it conducts away 970 B.t.u. of heat at a constant temperature of 212° F. but one pound of dry air heating up 100° F. conducts away scarcely 25 B.t.u. of heat.

Changes may be made in the details of construction and in the form and arrangement of parts without departing from the scope of the invention defined by the appended claims.

30 I claim:

1. In a reciprocating piston engine of the double acting type, a cylinder with a piston reciprocating therein, said cylinder having a centrally arranged inlet with a channel extending part way around said cylinder barrel for admitting a circulating agent to the inside of the cylinder barrel and at a point part way around the inside of the cylinder barrel and outlet with a channel extending part way around the cylinder barrel provided for said circulating agent to leave, a piston longer than the stroke of said piston provided with a sealing means adjacent its ends, said sealing means located a greater distance apart than the stroke of said piston and so located that a positive seal against leakage of said circulating agent into the ends of said cylinder barrel can be made effective, said piston provided with a spool type of passageway between its outer surface and the surface of the cylinder barrel extending completely around the piston and from the sealing means at one end to the sealing means at the other end of said piston, said spool type of passageway always in communication with the inlet and outlet openings and channels in the cylinder barrel provided for the circulating agent, said piston provided with a jacketing means through the heads thereof so a part of the circulating agent can circulate therethrough and around the end of the piston rod in said piston and said cylinder provided with a means closing the ends thereof.

2. In a reciprocating piston engine of the double acting type, a cylinder with a piston reciprocating therein, said cylinder having a plurality of centrally arranged inlets each having a channel extending part way around said cylinder barrel for admitting a circulating agent to the inside of the cylinder barrel, said inlets so located that the side thrust imposed upon said piston by fluid entering one inlet is balanced off by the side thrust imposed by fluid entering the remaining inlets; thereby allowing the piston to reciprocate freely with very little, if any, wear against said cylinder barrel and at suitably located points between said inlets in said cylinder barrel outlets with channels being provided for said circulating agent to leave, a piston longer than the travel of said piston provided with a sealing means adjacent its ends, said sealing means located a greater distance apart than the travel of said piston and so located that a positive seal against leakage of said circulating agent into the ends of said cylinder barrel can be obtained, said piston provided

with a spool type of passageway between its outer surface and the surface of the cylinder barrel extending completely around the piston and from the sealing means at one end to the sealing means at the other end and having parallel partitions located length ways along the piston, said partitions forcing a large part of the circulating agent to flow through jackets provided in the piston heads and around the piston rod on its way to the outlet channels and outlets in the side of said cylinder barrel provided for said circulating agent to leave, said passageways and piston head jackets always in communication with said inlets, outlets and channels in said cylinder barrel for said circulating agent and said cylinder provided with a head means closing both ends thereof.

3. In a reciprocating piston engine of the double acting type, a cylinder with a piston reciprocating therein, said cylinder having centrally arranged inlets and channels extending part way around said cylinder barrel for admitting a circulating agent to the inside of the cylinder barrel and at a point between said inlets and channels; outlets and channels extending part way around said cylinder barrel provided for said circulating agent to leave, a piston longer than the travel of said piston provided with a sealing means adjacent its ends, said sealing means located a greater distance apart than the travel of said piston and so located that a positive seal against leakage of said circulating agent into the ends of said cylinder barrel can be made effective, said piston provided with a spool type of passageway around its outer surface between it and the cylinder barrel extending completely around the piston and from the sealing means at one end to the sealing means at the other end of said piston, said spool type of passageway always in communication with the inlet and outlet openings and channels in the cylinder barrel provided for the circulating agent to enter and leave, partitions properly located along the sides of said piston to restrict the flow of said circulating agent around the sides of said piston so a part of said circulating agent must pass through jackets provided in the heads of said piston and around the piston rod, said

6
cylinder provided with a means for closing both ends thereof.

4. In a reciprocating piston engine of the double acting type, a cylinder with a piston reciprocating therein, said cylinder having a centrally arranged inlet and a channel extending part way around said cylinder barrel for admitting a circulating agent to the inside of the cylinder barrel and at a point part way around the cylinder barrel an outlet and a channel extending part way around said cylinder barrel provided for said circulating agent to leave, a piston longer than the stroke of said piston provided with a sealing means adjacent its ends, said sealing means located a greater distance apart than the stroke of said piston and so located that a positive seal against leakage of said circulating agent into the ends of said cylinder barrel can be made effective, said piston provided with a spool type of passageway around its outer surface between it and the cylinder barrel extending completely around the piston and from the sealing means at one end to the sealing means at the other end of said piston, said spool type of passageway always in communication with the inlet and outlet openings and channels provided in the cylinder barrel for the circulating agent to enter and leave, said cylinder provided with a head means for closing both ends thereof.
